SPARK PLUG

Filed Nov. 29, 1921

Inventor
M. Rothberg & J. Lalava

By Attorney

UNITED STATES PATENT OFFICE.

MURRAY ROTHBERG AND JOHN LA CAVA, OF BROOKLYN, NEW YORK.

SPARK PLUG.

Application filed November 29, 1921. Serial No. 518,589.

To all whom it may concern:

Be it known that we, MURRAY ROTHBERG and JOHN LA CAVA, citizens of the United States, residing at Brooklyn, in the county 5 of Kings and State of New York, have invented certain new and useful Improvements in Spark Plugs; and we do hereby declare the following to be a full, clear, and exact description of the invention, such as 10 will enable others skilled in the art to which it appertains to make and use the same.

The invention relates to spark plugs for the ignition system of explosive engines and its primary intent is the provision of a 15 double-ended spark plug which may be reversed thereby performing the same office as two independent spark plugs at practically the same cost of a single spark plug.

The invention consists of a shell or body 20 provided at opposite ends with adjustable electrodes, a core of insulating material within the shell, an electrode carried by the core and projecting beyond the ends thereof to cooperate with the electrodes of the shell, 25 and a cap detachably fitted to either end of the shell and provided with a binding post to make electrical connection with either end of the electrode carried by the core according to which ever end of the shell the cap 30 is applied to.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to 40 without departing from the nature of the invention.

Referring to the accompanying drawings forming a part of the application,

Figure 1 is an elevation of a spark plug 45 embodying the invention,

Figure 2 is a central longitudinal section thereof,

Figure 3 is an elevation of the shell or body, the cap being omitted, and

Figure 4 is an end view of the cap.

Corresponding and like parts are referred to in the following description and designated in the several views of the drawings by like reference characters.

The spark plug comprises a shell or body 55 1 having an inner shoulder 2 and a centrally disposed polygonal portion for the reception of a wrench or spanner. Opposite end portions of the shell 1 are externally screw threaded as at 1^a to admit of either end being coupled to the engine in the usual way. Each end of the shell or body 1 is provided with an electrode 3 which is adjustable to admit of either electrode being turned aside to be out of the way and the 60 other electrode to be moved into operative position. The two positions of the electrodes are shown most clearly in Figures 2 and 3.

A core 4 of insulating material is disposed within the shell or body 1 and has an 70 outer shoulder 5 which engages the inner shoulder 2, a nut 6 threaded into the shell serving to secure the core 4 within the shell, as clearly indicated in Figure 2. A gasket is fitted about the shouldered portion 5 of 75 the core 4 and comprises a metal sleeve 15 and packing 16, the ends of the sleeve 15 being crimped about the ends of the part 5 and the packing 16 being disposed to come between adjacent shoulders 2 and 5. An 80 electrode 7 is secured centrally within the core 4 and its end portions project beyond the core and are externally screw threaded. Points 8 are fitted to opposite ends of the electrode 7 and form extensions thereof and 85 are adapted to cooperate with the electrodes 3. Washers 17 are held against the ends of the core 4 by nuts 18 threaded on the projecting ends of the electrode 7.

A cap 9 of insulating material is adapted 90 to be fitted to either end of the shell or body 1 and is provided with an inner tubular extension 10 which is adapted to receive either end of the electrode 7 according to the position of the cap on the shell or body 1. 95 The tubular extension 10 is likewise of insulating material and is preferably separate from the cap.

A piece of felt 20, or like material, is let into a notch formed in the inner end of the 100

part 10 and acts as a wiper to remove soot, carbon or the like adhering to the outer side of the end of the core 4 that has become foul from use, thereby preventing short circuiting of the plug, when reversed. When placing the cap 9 upon the used end of the plug the wiper 20 in moving about the end of the core removes any soot, carbon or the like clinging thereto. The wiper 20 projects 10 beyond the inner wall of the part 10 to engage the outer surface of the core.

A binding post is carried by the cap 9 and comprises a threaded stem 11 and a tubular portion 12, the latter being disposed within 15 the tubular extension 10 and the stem 11 projecting beyond the end of the cap and receiving a washer 13 and a binding nut 14, the washer 13 comprising suitable packing having a metal insert crimped there about, 20 and the nut 14 operating as means for securing the usual lead wire to the spark plug. The tubular portion 12 is internally screw threaded to match the externally threaded portion 19 of the electrode 7, whereby to secure 25 the cap to the shell or body 1 and insure positive connection between the binding post and the electrode.

In practice, the cap 9 is fitted to an end of the shell or body, the electrode 3 housed by 30 the cap being turned aside, as indicated in Figure 2 and the electrode 3 of the exposed end being turned to cooperate with the point 8 of the electrode 7 to form the usual spark gap for a purpose well understood. In the 35 event of the spark plug fouling at one end, or failing to function properly, the cap 9 may be detached and the body of the plug and the electrodes 3 reversed and the cap applied to the end previously coupled to 40 the engine with the result that the plug presents a new working end in substantially the same manner as a new plug, thereby saving time and obviating the necessity of carrying extra plugs for an emergency and 45 besides minimizing the cost, since the article may be provided at substantially the same cost as the ordinary single spark plug.

What is claimed is:

1. A reversible spark plug comprising a 50 shell and a core of insulating material secured within the shell and having projecting end portions spaced from the shell, an electrode carried by the core and at each end coacting with the shell to provide a 55 spark gap, a cap constituting a terminal for a conductor and adapted to be fitted to either end of the shell, a tubular element carried by the cap and adapted to receive either end of the core, and a wiper carried 60 by said tubular element for removing soot or other accumulation tending to foul and short circuit the plug.

2. A spark plug comprising a shell, a core 65 of insulating material within the shell and

having its end portions spaced therefrom, 65 an electrode carried by the core and coacting with the shell to provide spark gaps adjacent said portions, a cap constituting a binding means for a conductor and adapted to selectively close either end of the shell, 70 and a wiper carried by the cap adapted to engage the adjacent surfaces of the core to remove soot and the like therefrom when removing or replacing the cap.

3. A spark plug comprising a shell, a 75 core of insulating material within the shell, an electrode carried by the core and having its end portions providing spark gaps between the same and the shell, a cap constituting a binding means for a conductor and applicable to either end of the shell, said cap being provided with an element adapted to enter said spaces between the shell and core, and a wiper carried by said element and movable with the cap when placing it 80 in position or removing it from the shell.

4. A spark plug comprising a shell, a core of insulating material within the shell, an electrode within the core and having its ends projecting beyond the core and threaded, 90 said electrode providing spark gaps between the same and the shell, a cap constituting a binding means for a conductor, said cap having screw threads applicable to the screw threads of the electrode at either end 95 of the shell, and a wiper carried by the cap and adapted to engage the core to remove soot therefrom when placing the cap in position or removing it from the plug.

5. A spark plug having a shell, a core of 100 insulation therein spaced at the sides of its end portions from the inner wall of the shell, and an electrode carried by the core, electrodes carried by the shell one adjacent each 105 end to provide spark gaps between the same and the first electrode, a cap applicable to either end of the electrode having a binding post thereon for a conductor, a tube carried by the cap disposable in the spaces between the ends of the core and the shell, said 110 binding post being surrounded by said tube, and the second mentioned electrode being movable relatively to the first mentioned electrode to accommodate the reception of 115 said tube within the plug.

6. A spark plug having a shell, a core of insulation therein spaced at the sides of its end portions from the inner wall of the shell, and an electrode carried by the core, electrodes carried by the shell one adjacent 120 each end to provide spark gaps between the same and the first electrode, a cap applicable to either end of the electrode having a binding post thereon for a conductor, a tube carried by the cap disposable in the spaces 125 between the ends of the core and the shell, said binding post being surrounded by said tube, the second mentioned electrode being

movable relatively to the first mentioned electrode to accommodate the reception of said tube within the plug, said tube extending inwardly beyond said binding post, and
5 a wiper carried by the tube adjacent its inner end and adapted to clean the plug adjacent the spark gap through removal and application of the cap.

In testimony whereof we affix our signatures in the presence of two witnesses.
